UNITED STATES PATENT OFFICE.

WILLIAM JOHN McGEE, OF DAISY, GEORGIA.

DUMPING-WAGON.

1,245,000.

Specification of Letters Patent.

Patented Oct. 30, 1917.

Application filed October 20, 1916. Serial No. 126,794.

To all whom it may concern:

Be it known that I, WILLIAM JOHN McGEE, a citizen of the United States, and a resident of Daisy, in the county of Evans and State of Georgia, have invented a new and useful Improvement in Dumping Wagons, of which the following is a specification.

My present invention relates generally to dumping wagons, and more particularly to a dumping wagon the bottom of which consists of a plurality of dumping slats, my object being to so arrange the dumping slats and to provide such an operating mechanism in connection therewith that the dumping of the wagon, even under heavy load, may be accomplished readily and quickly without strain either upon the slats themselves or the operating devices connected therewith.

The further objects of my present improvements, residing as they do for the most part in the details of construction, will be better understood from the following description, referring to the accompanying drawings forming a part of this specification, in which—

Figure 1 is a side elevation of a wagon equipped with my improvements.

Fig. 2 is a horizontal section taken therethrough substantially on line 2—2 of Fig. 1.

Fig. 3 is a front elevation.

Fig. 4 is a vertical cross section taken substantially on line 4—4 of Fig. 2.

Fig. 5 is a detail vertical section taken substantially on line 5—5 of Fig. 2, and

Fig. 6 is a similar view taken substantially on line 6—6 of Fig. 5.

Referring now to these figures, and particularly to Fig. 2, it will be noted that the wagon box or body is in accordance with my improvements provided with a bottom in the form of a plurality of independent slats 11, arranged in forward and rear transverse series, upon relatively opposite sides of an intermediate bottom cross strip 12, having bearings or shafts 13 connecting the aligned slats of the two series.

It will be noted particularly from Fig. 2 that the shafts 13 extend from the inner ends of the slats 11 at one side of the center thereof so that, with the aligned trunnions 14 at the outer ends of the slats, the latter are eccentrically mounted and swingable laterally to and from the dumping position as shown in full lines in Fig. 4.

The shafts 13 and trunnions 14 extend longitudinally from the slats 11 in the same

plane therewith, the ends of the slats 11 having cut-out portions, one of which may be plainly seen at 15 in Fig. 5, receiving the adjacent end of the respective shaft or trunnion, which latter is held in position by means of a rivet 16 extending therethrough and through a reinforcing bar 17 secured transversely of the respective slat, each slat having a reinforcing bar 17 at each end thereof.

The trunnions 14 at the outer ends of the slats 11 extend through bearings 18 in the front and rear walls of the box or body 10, upstanding cranks 19 being rigidly secured 70 to the exteriorly projecting ends of the trunnions and pivotally connected to a connecting bar 20 exteriorly of the respective end of the box or body 10 and thus connecting the several slats 11 of the forward or 75 rear series for simultaneous movement.

Each connecting bar 20 is also pivotally connected at 21 to a reach-rod 22, the reach rod at the forward end of the box or body 10 being pivotally connected at its opposite 80 end to a lever 23 and the reach-rod 22 at the rear end of the box or body being connected to a lever 24, said levers 23 and 24 being secured to the forward and rear ends respectively of a shaft 25 journaled longitudinally of the box or body 10 at one side thereof and extending throughout its full length, so that the forward and rear series of slats 11 may be simultaneously operated 85 from either of the levers mentioned and hence from either the forward or rear end of the box or body 10.

The forward lever 23 is preferably provided with a latch mechanism 26 in engagement with a stationary quadrant 27 secured 95 to the box or body 10 so as to permit of locking the slats in the closed position in dotted lines in Fig. 4.

It is obvious, therefore, that in view of my improved arrangement of the slatted bottom and the particular means for moving the slats, the contents of the box or body 10 may be dumped from the forward or rear end thereof, or by operators at both ends, applying power simultaneously to the levers 100 23 and 24.

It is also obvious that in view of the eccentric type of mounting of the slats 11, their opening movement will necessarily be assisted by the gravity and weight of the 110 material contents of the box or body 10, so as to assist in such movement.

It is also to be seen that in view of the particular connections of the slats 11, they may in case of wear or accident, be quickly repaired and readily replaced, and that their arrangement provides for convenient manipulation and operation in connection with farm and other wagons of considerable wheel base.

I claim:—

- 10 A wagon box or body having an intermediate lower cross strip and series of laterally opening slats forming the bottom or base thereof, arranged upon opposite sides of the said cross strip, shafts connecting the adjacent ends of the said slats and having bearings in the said cross strip, trunnions at the outer ends of the several slats having bearings in, and projecting beyond, the forward and rear ends of the box or body, 15 cranks secured to the exteriorly projecting
- 20

ends of said trunnions, an operating shaft journaled longitudinally within the lower portion of the box or body, and having operating levers in its opposite ends, and connections between the said levers and the cranks of the respective series of slats, each of said slats having cut-out portions at its opposite ends into which the extreme ends of the connecting shafts and the trunnions project in the same plane with the slats, and cross bars extending across the faces of the slats and rigidly connected intermediate their ends to the said ends of the connecting shafts and trunnions, said cross bars being also secured to the said slats, whereby to reinforce the latter and support the said shafts and trunnions in connection therewith.

WILLIAM JOHN McGEE.

Copies of this patent may be obtained for five cents each, by addressing the "Commissioner of Patents, Washington, D. C."
